UNITED STATES PATENT OFFICE.

EDGAR A. BENNETT, OF PROVIDENCE, RHODE ISLAND.

FOB-BAR.

SPECIFICATION forming part of Letters Patent No. 737,062, dated August 25, 1903.

Application filed May 29, 1903. Serial No. 159,267. (No model.)

To all whom it may concern:

Be it known that I, EDGAR A. BENNETT, a citizen of the United States, residing at Providence, in the county of Providence and State 5 of Rhode Island, have invented certain new and useful Improvements in Fob - Bars, of which the following is a specification, reference being had therein to the accompanying drawings.

My invention relates to the bars from which fobs depend and when constructed as herein set forth may be utilized for ornamental or supporting purposes intermediate the length of the fob. It is designed for use upon fabric fobs and has for its primary purpose a facile and cheap means of engaging the fabric and without the use of solder.

Another purpose is to provide a means of fastening which while secure will admit disengagement of parts without defacement whenever it is desired to substitute a fresh fob-ribbon or expose an unsoiled portion of the worn ribbon.

To the above ends my invention consists 25 in the novel arrangement and combination of parts hereinafter set forth, and illustrated in the accompanying drawings, wherein—

Figure 1 is a perspective view of a fob provided with my new bar; Fig. 2, a like view 30 of the shell or sleeve portion of the bar; Fig. 3, a transverse section of the latter on line *a* *a* of Fig. 2; Fig. 4, a perspective view of the tube or core; Fig. 5, a transverse section of the latter on line *b* *b* of Fig. 4; Fig. 6, a detail view of the securing-pins; Fig. 7, a perspective view of the parts in progress of assemblage; Fig. 8, a longitudinal section of the shell of the completely-engaged bar, showing the pins in side elevation; and Fig. 9, a transverse section of the engaged bar on line *c* *c* of Fig. 8.

Like reference-letters indicate like parts throughout the views.

In detail my bar consists of a cylindrical shell or sleeve *d*, composed of gold, brass, or other springy metal, provided with a longitudinal slit or opening *e* and a suspension-ring *f*. A cylindrical core *g*, preferably tubular in form and of less external diameter than the 45 internal diameter of the shell, is designed for

insertion within the latter. The ribbon *h* of the fob surrounds this core intermediate the same and the shell. As security against any displacement of the parts it is advantageous to insert within each end of the tube a pin *i*, 55 provided with an enlarged head *k*, which abuts against the ends of the assembled parts. The diameter of the pin - shank *i* is sufficiently great to engage the tube frictionally. While slit caps swaged over the exposed ends of the fob - bar might insure the parts against displacement, I find the use of pins more practical and more ornamental.

The parts are assembled thus: The ribbon *h* is folded over an oblong thin metal blade 60 *l*, Fig. 7, and forced through the slit *e* of the shell *d* into contact with the inner wall thereof, whereupon the blade *l* is longitudinally withdrawn and the core *g* inserted into the fabric-lined shell. The pins *i* are next forced into 65 the ends of the core, and the heads *k* insure the assembled parts against displacement whenever the friction between the assembled parts are insufficient for the purpose.

I find my new bar adapted not only for the 75 suspension of the fob, but also applicable for ornamental purposes upon the face of the ribbon, as *d'*, Fig. 1, whereon may be suspended from the ring *f'* any desired ornament or locket *m*.

Having described my invention, what I claim as new, and desire to secure by Letters Patent, is—

1. In a fob-bar, the combination with an outer shell provided with a longitudinal slit, 85 of a core within the shell provided with openings in its extremities, pins adapted to enter the openings, and heads upon the pins.

2. In a fob-bar, the combination with an outer shell provided with a longitudinal slit, 90 of a tubular core within the shell, and tapering members provided with enlarged extremities adapted to frictionally enter the ends of the core and abut against the shell.

3. In a fob, the combination with the ribbon provided with a transverse fold of a core within the fold, a shell over the fold adapted to hold the ribbon in contact with the core, and means upon the extremity of the core for preventing displacement of the parts.

4. In a fob, the combination with the ribbon provided with a transverse fold of a core within the fold, means upon the exterior of the fold for holding the ribbon in contact with the core, and means frictionally engaging the core for preventing displacement of the parts.

In testimony whereof I have affixed my signature in presence of two witnesses.

EDGAR A. BENNETT.
